ABRADING OR POLISHING MACHINE

Charles Johnson and Carl Lawrence Mattison,
Rockford, Ill., assignors to Mattison Machine
Works, Rockford, Ill., a corporation of Illinois

Application June 29, 1932, Serial No. 619,836

10 Claims. (Cl. 51—135)

One of the objects of the invention is to provide novel and improved means for driving the abrading or polishing belt and for pressing the belt against the work.

Another object is to provide novel and improved means for reciprocating the presser carriage.

Another object is to produce a novel machine in which the abrading or polishing operation may be performed either through the medium of the usual endless belt or directly by the presser roll which presses the belt against the work.

A further object is to provide a presser carriage of novel construction by which the position of the presser roll may be varied to accommodate work of different thicknesses.

In the accompanying drawings, Figure 1 is a front elevation with parts broken away showing a machine embodying our invention.

Fig. 2 is an elevational view illustrating the mechanism for reciprocating the presser carriage.

Fig. 3 is a vertical front-to-rear sectional view through said carriage.

Fig. 4 is a rear elevation of the carriage showing a modified form of means for driving the presser roll.

The present invention is applicable to a machine of the general type disclosed in Patent No. 1,478,044, issued December 18, 1923, to Carl Lawrence Mattison, but in the present application we have shown only such parts of the machine as are necessary to an understanding of the invention.

It should be understood that the present invention is susceptible of embodiment in various forms and alternative constructions, and that the illustration by way of example of one preferred embodiment of the invention is not to be taken as an intention to limit the invention to the present disclosure. The scope of the invention will be pointed out in the appended claims.

The machine comprises a pair of pedestals 10 connected at their upper ends by a support 11 upon which the various operating mechanisms are carried. The pedestals also carry tracks 12 running from front to rear upon which the work supporting table 13 is mounted. A pair of spaced hold-down rollers 14 are journaled in bearings on the pedestals in overlying relation to the work table and act to press against the work table the piece of work A, 55 which may be a sheet of steel, and thereby pre-

vent buckling or warping of the sheet due to the heat generated therein by the abrading mechanism.

The endless abrasive belt 15 is supported upon two idler pulleys 16 which are suitably journaled on the machine frame and the lower or active run of this belt runs around rolls on a carriage 17 which is mounted on a horizontal rail 18 to reciprocate longitudinally of said belt.

This carriage 17 is reciprocated by means of an endless cable 19 running over a pair of sheaves 20 journaled on the machine frame, one of which sheaves is driven alternately in opposite directions by a reversible electric motor 21 and suitable reduction gearing 22. The carriage has means to be presently described for attaching it to the lower run of said cable 19.

Means is provided for automatically reversing the electric motor 21, which means in the exemplary embodiment herein shown is actuated by the movement of the carriage 17. A reversing switch 23 mounted on the machine has a pair of contacts 24 and a pivoted switch arm 25 which contacts and arm are connected by wires 26 to the reversing fields of the motor 21 in a manner well known. The switch has a spring 27 fastened to the arm 25 acting to hold the arm in engagement with either one of the contacts 24, with the result that the motor will be driven in one direction or the other depending upon which one of the contacts the arm engages. A rod 28 slidably mounted in bearings 29 on the machine frame has a pair of projections 30 embracing the switch arm 25, and the rod also carries a pair of collars 31 which are adjustable along the rod and are secured thereto by suitable means such as set screws. These collars are in position to be engaged by a part on the carriage 17 in its reciprocation to effect alternate longitudinal movement of the rod in opposite directions and thereby swing the switch arm 25 from one of the contacts 24 to the other. It will thus be seen that by setting the collars 31 at different distances apart, the range of reciprocation of the carriage may be varied and controlled.

The carriage comprises two sections, one of which, designated 17^a, is equipped with a plurality of rollers 32 to run upon a guide rail 18. The other section 17^b of the carriage is mounted 50 for vertical sliding movement upon the first mentioned section.

The means for connecting the carriage to the reciprocating cable 19 may be of any suitable form, that herein shown comprising an arm 55

33 (Fig. 3) projecting rearwardly from the carriage section 17^a and having a finger 34 to engage between a pair of stops or collars 35 fixed on the cable 19.

5 The lower carriage section 17^b is mounted on vertical guideways 36 on the upper section and is held by a vertical screw 37 rotatably mounted in the lower section and threaded in a lug 38 on the upper section, which lug passes through 10 a slot 39 in the lower section. A collar 40 fixed on the screw 37 prevents endwise movement of the screw relative to the lower section so that by rotating the screw the lower carriage section may be adjusted vertically by the operator.

15 In the lower carriage section are mounted a pair of idler rolls 41 and a combined driving and belt pressing roll 42. The lower run of the abrasive belt 15 passes over the top of the two idler rolls and down underneath the driving and 20 pressing roll 42. The belt is thus flexed sharply out of the plane of the lower run thereof to form a relatively small loop which accomplishes a two-fold purpose in that it insures driving traction between the presser roll 42 and the belt 25 and it gives the belt a much more efficient cutting action. In passing around these carriage rolls, the belt is sharply flexed in alternately reversed directions which acts to loosen dust or foreign matter that always tends to pack in between the abrasive grains and which, if not removed, would eventually cause the belt to glaze with the result that its cutting action is impaired and more heat is generated. As the belt passes around the presser roll 42 the particles of 30 abrasive are spread apart so that their cutting edges are more effectively brought into action along the zone of contact with the work. It has been found that this greatly increases the efficiency of the abrading action and also permits worn particles of abrasive to free themselves and escape from the belt and thereby 35 present fresh sharp particles into cutting engagement with the work. The length of life of the belt is thus increased.

40 The presser roll 42 is preferably made of or surfaced with a yielding or cushion material which compresses very slightly under the existing pressure to maintain a narrow zone of contact between the belt and the work a little wider than a mere line contact. It has been found that providing a contact zone about three-eighths of an inch in width gives the most efficient cutting action.

45 The idler rolls 41 are mounted on the carriage in such position that the upper surfaces of said rolls lie substantially in the plane of the lowermost points on the periphery of belt supporting pulleys 16 so that the tension upon and deflection of the belt in its passage through the carriage 17 will remain constant in all positions 50 of the carriage in its reciprocation.

55 In prior machines of this type, the abrasive belt has usually been driven by one of the pulleys 16. It has been found that driving the belt from the presser roll on the carriage greatly reduces the strain on the belt and the liability of danger of its tearing or breaking; also that the quality of the work is improved because the surface of the presser roll does not have a tendency to be roughened by the belt and there is less tendency to vibration or chattering at the point of contact of the belt with the work than is the case where the belt is driven from one of the 60 pulleys 16.

65 It is, therefore, one of the important features

of the present invention to mount on the carriage power means for driving the presser roll and, through said roll, the abrasive belt 15. The arrangement of this power driving means may be varied to suit requirements. In the present 5 instance we have shown in Figs. 3 and 4 two alternative constructions. Referring first to Fig. 3, the presser roll 42 is mounted on a shaft 43 journalled in the carriage and this shaft constitutes an extension of or is axially alined with 10 and fixed to the armature shaft of an electric motor 44 which is secured beneath a rearwardly projecting portion of the lower carriage section. It will be noted that the presser roll 42 is positioned between the two hold-down rollers 14 and 15 the electric motor 44 is located rearwardly of the rear one of said hold-down rollers, the shaft 43 overlying the latter roller.

15 In the alternative construction illustrated in Fig. 4, the motor 44 is mounted on the carriage 20 in a position offset from or out of alinement with the presser roll 42, and power is communicated from the motor to said presser roll by a belt 45 running over sheaves 46 fixed respectively on the armature shaft and the shaft of said 25 presser roll. By replacing the sheaves 46 with sheaves of relatively different diameters, the speed of the presser roll 42 may be varied at will.

30 It will be understood, of course, that suitable connections between the motors 21 and 44 to power lines and suitable controlling switches therefore are provided. It is not deemed necessary to illustrate this arrangement herein since it may be of conventional form and constitutes no 35 part of the present invention.

35 If desired, the abrasive belt may be removed from the machine and an abrasive or polishing sheet fastened about the periphery of the presser roll 42, or instead the presser roll may be 40 removed from the carriage and another roll having abrasive or polishing material on its periphery may be substituted therefor.

45 In operation the sheet of material A to be finished is laid upon the work table 13 while the table is in its foremost position. The table is then pushed rearwardly to carry the sheet beneath the hold-down rollers 14. Either the supporting rails 12 for the work table or the bearings for the hold-down rollers 14 or both 50 may be made vertically adjustable to vary the space between said hold-down rollers and the upper surface of the work table for accommodation of work of different thicknesses. The construction of the carriage 17 also permits, 55 through manipulation of the screw 37, a micrometer adjustment of the height of the presser roll 42. To control the range of reciprocation of the carriage to accord with the width of the work piece, the operator may adjust the stop 60 collars 31 on the rod 28 so that the switch 23 will be reversed when the carriage has traveled a desired distance in either direction. When the proper relationship has been established, the motors 21 and 44 may be started and so long as 65 the carriage is coupled to the cable 19 the carriage will be reciprocated along its guide rail, with the abrasive belt 15 or the abrading or polishing surface of the roll 42, as the case may be, in contact with the work A. The work table 70 is moved rearwardly either by hand or by power as the carriage reciprocates so that every point on the sheet A will be treated. If desired, the arm 33 on the carriage may be disengaged from the driving cable 19 and the position of the 75

carriage may be then manually controlled so that the operator may give further or special treatment to any spots on the work which have not been finished to the desired degree.

5 We claim as our invention:

1. A machine of the character described having, in combination, an endless belt to operate on the work, a plurality of idler pulleys supporting said belt, and means for driving said belt and for pressing the belt against the work comprising a carriage mounted to reciprocate along said belt, a power-driven presser roll on said carriage frictionally engaging and driving said belt and pressing the belt against the work, and a pair of idler rolls located at opposite sides of and close to said presser roll and acting to hold said belt in contact with said presser roll and to cause alternate reverse flexing of the belt so as to free foreign matter and to spread 10 the abrasive particles apart at the zone of engagement with the work for better cutting action.

2. A machine of the character described having, in combination, an endless abrading or polishing belt, a plurality of pulleys supporting said belt, and means for driving said belt and for pressing the belt against the work comprising a carriage mounted to reciprocate parallel to the active run of the belt, a presser roll mounted on 15 said carriage in driving engagement with the belt and arranged to press the belt against the work, a pair of idler rolls mounted on said carriage on opposite sides of and close to said presser roll and holding said belt against said presser roll, and a motor mounted on said carriage for driving said presser roll and thereby driving said belt.

3. A machine of the character described having, in combination, an endless abrading or polishing belt, a carriage mounted to reciprocate along the active run of said belt, a plurality of rolls mounted on said carriage over which rolls said active run of the belt passes, one of said rolls acting to press the belt against the work, and power means on said carriage for driving the last mentioned roll and thereby driving said belt.

4. A machine of the character described having, in combination, an abrading or polishing belt, means for supporting said belt, and means for driving said belt and for pressing the belt against the work comprising a carriage mounted to reciprocate along the active run of said belt, a pair of idler rolls on said carriage engaging said belt, a presser roll mounted on said carriage between and close to said idler rolls and engaging said belt to deflect a loop thereof sharply out of the plane of the remainder of the active run of the belt for engagement with the work, and a motor mounted on said carriage for driving said presser roll and thereby driving said belt.

5. A machine of the character described comprising, in combination, means for supporting a piece of work, work hold-down means overlying said work supporting means, abrading or polishing means including a carriage mounted to reciprocate along the work, a presser roll on said carriage, and a driving motor on said carriage

operatively connected to said roll, said roll and said motor being located at opposite sides of said hold-down means.

6. A machine of the character described having, in combination, a horizontal work table, a pair of hold-down rollers overlying said work table, abrading or polishing means above said work table including a carriage mounted for horizontal reciprocation parallel to said rollers, a presser roll on said carriage located between said hold-down rollers for pressing the abrading or polishing means against the work, and a driving motor mounted on said carriage and drivingly connected to said roll, said motor being located at the outer side of one of said hold-down rollers relative to said presser roll.

7. A machine of the character described having, in combination, an endless belt for operating on the work and having a plain and an abrasive side, a plurality of idler pulleys supporting said belt to provide a run with a straight portion, a power-driven presser roll frictionally engaging the plain side of said belt at the straight portion of the run to drive the belt, and a pair of idler rolls located at opposite sides of and close to said presser roll and engaging the abrasive side of said belt, said presser roll being offset relative to said idler rolls to deflect the belt into engagement with the work and to cause the belt to contact with a substantial portion 30 of the periphery of said presser roll to insure proper driving traction between the latter and said belt.

8. A machine of the character described having, in combination, an endless belt for performing a working operation, a carriage mounted for reciprocation along a piece of work and longitudinally of said belt, a plurality of rolls mounted on said carriage over which said belt passes, one of said rolls acting to press a face of said 35 belt against the work to perform a working operation, and power driven means on said carriage drivingly connected with one of said rolls for driving said belt.

9. A machine of the character described having, in combination an endless abrading or polishing belt, a carriage mounted to reciprocate along the active run of said belt, a roll mounted on said carriage over which the active run of the belt passes and by which the belt is pressed 50 against the work, and power means on said carriage for driving the last mentioned roll and thereby driving said belt.

10. In a machine of the character described, the combination of a frame having a work supporting face, an endless belt having an active run extending substantially parallel to said face, a pair of hold-down rollers disposed adjacent to said face and located in substantial parallelism, one on each side of said active run, a reciprocating carriage mounted for movement longitudinally of said active run, and a driven roll mounted on said carriage and engaging said active run for driving said belt and for pressing it against the work between said hold-down 60 rollers.

CHARLES JOHNSON.
CARL LAWRENCE MATTISON.
